Inventor

Louis C. Vanderlip.

UNITED STATES PATENT OFFICE.

LOUIS C. VANDERLIP, OF ELKHART, INDIANA.

HOOD LATCH.

Application filed May 24, 1926. Serial No. 111,137.

This invention relates to automobiles, and especially to the hood latch therefor.

The principal object of this invention is to provide a simplified hood latch in which 5 the resilient and extensible body element thereof exerts both a downward pressure or pull and also a lateral inward thrust on the hood to retain the hood in position and to prevent rattling thereof.

10 Another object of the invention is to provide a simple and cheap form of automobile hood latch in which the body element thereof is composed of a flat piece of steel provided with a resilient loop or return 15 bend to enable extensibility of the body element.

Other objects of the invention are mentioned and described herein.

The preferred embodiment of the invention is illustrated in the accompanying drawing in which Figure 1 is a side elevation of the improved hood latch in its operative position, a fragment of the hood being illustrated in connection therewith; 25 Fig. 2 is a rear elevation thereof and a hood fragment; Fig. 3 illustrates two views of the latch element alone at right angles to each other; and Fig. 4 is a section taken on line 4-4 of the left hand view of Fig. 3.

30 Similar numerals of reference indicate like parts throughout the several views on the drawing.

In automobile hood latch design it is essential that the clamping device exert both 35 a downward pull and a lateral thrust on the hood in order to effect the maximum efficiency in hood retention and rattle prevention. It is also desirable to effect the maximum simplicity of design and construction 40 in a hood latch, as in other mechanical devices, and in that respect I have produced a device which is extremely simple and very cheap, as well as very durable and rugged.

A reference to the details of the drawing 45 indicates that the numeral 1 represents a part of an automobile frame, longitudinally of which an abutment element 2 is arranged and rigid therewith. Numeral 3 indicates a fragment of one side of the automobile engine hood, well known in the art, which is vertically disposed and adapted to engage the abutment 2 when pressed inwardly by the clamping element or means hereinafter described. A latch keeper 4 of the usual, 55 or any suitable, type may be rigidly secured

to the hood exterior at any suitable distance above the frame section 1.

The clamping means of my improved hood latch may consist of the flat steel body element 5 provided with a spring loop or lateral return bend 6, preferably integral therewith, and intermediate the extremities thereof, and the latch element 7 rigidly secured to the upper end of said body element in any suitable manner, as by rivets 8. The 60 latch element 7 may be provided with the hook 9, adapted to engage the keeper 4, and the handle 10 to enable the operator to extend the body 5 by resiliently stretching the 65 loop 6.

70 The lower end of the latch body 5 may be provided with an eye 11 for hinge connection with the pin 12 mounted in a forked bracket 13, the latter being rigidly secured to the base element 1 in any suitable manner.

A rubber buffer 14 may be secured to the face of the loop section 6 of the latch body to prevent abrasion of the paint on the hood exterior and to eliminate contact of 80 metal on metal.

It will be obvious that my improved hood clamp provides a simple unitary clamping element composed of the longitudinally extensible body 5 and the resilient side engaging loop 6, whereby a downward pull is exerted on the hood 3 together with a simultaneous inward lateral thrust thereon, thereby effectually preventing both upward and lateral movement of the hood.

90 I claim:

1. In an automobile hood clamp, a unitary hold-down clamp and a side engaging element, the latter constituting resilient means to enable longitudinal extensibility 95 of the former.

2. In an automobile hood-clamp, a unitary hold-down clamp and a resilient laterally projecting side engaging clamp rigid therewith, said hold-down clamp including a separate element latch member.

3. In an automobile hood-clamp, the combination of a flat metal body element provided with a resilient lateral bend adapted to effect lateral pressure on the hood, said 105 bend constituting resilient means to enable longitudinal extensibility of the clamp body, and a hook and handle rigidly connected with the upper end of said body element.

4. In an automobile hood clamp, a unitary 110

hold-down clamp and a resilient laterally projecting side engaging clamp integral therewith.

5. In an automobile hood-clamp, a unitary hold-down clamp and a side engaging element, the latter constituting resilient means to enable longitudinal extensibility of the former, and a rubber buffer mounted upon said side engaging element.
10. 6. In an automobile hood clamp, the combination of a combined hold-down clamp and a side engaging element, the latter constituting resilient means to enable longitudinal extensibility of the former, a hook and

handle element carried at the top end of 15 said clamp, and a hinge eye carried at the bottom thereof.

7. In an automobile hood clamp, the combination of a flat metal body element provided with an integral lateral resilient loop 20 intermediate its extremities to enable longitudinal extensibility of said body element, a hook and handle element carried at the top of said body element, and an integral hinge eye carried at the bottom thereof. 25

In witness whereof I have hereunto affixed my signature this 20th day of May, 1926.

LOUIS C. VANDERLIP.
